(57) **CLAIM**

The ornamental design for an electric appliance for food fermentation, as shown and described.

DESCRIPTION

FIG. 1 is an isometric view of an electric appliance for food fermentation showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.

The broken lines in the figures represent features of the article of manufacture that form no part of the claimed design.
